Patented Oct. 8, 1918.

Fig. 1.

UNITED STATES PATENT OFFICE.

GEORGE H. FAHRENBRUCH, OF OMAHA, NEBRASKA.

RULE ATTACHMENT.

1,280,693.

Specification of Letters Patent.

Patented Oct. 8, 1918.

Application filed March 18, 1918. Serial No. 223,172.

To all whom it may concern:

Be it known that I, GEORGE H. FAHRENBRUCH, a citizen of the United States, residing at Omaha, in the county of Douglas and State of Nebraska, have invented certain new and useful Improvements in Rule Attachments, of which the following is a specification.

My invention relates to a new and useful improvement in attachment for rules of the foldable type, and has for an object to provide an attachment that is so constructed that when secured to the rule, the rule may be used as a square, furthermore the attachment is formed at its lower end with a slightly bent portion that forms a clip to be passed over the outer fold of a pocket so that the rule will not slip out of the pocket when the wearer bends over.

Another object of my invention is to form the attachment out of a single blank of metal, so that the same may be made in quantities with but little manufacturing expense, also one set of dies only is needed to stamp the attachments out in great numbers.

Also another object of the principal form of my invention is to so provide the attachment that its outstanding arm that functions as the one arm of the square will be exactly at right angles to the rule, and it will be impossible to fasten the attachment to the rule in any other than its correct position.

With these and other objects in view, my invention consists in certain new and novel constructions as will hereinafter be described and pointed out in the claims.

In the drawings;

Figure 1 is a view showing the rule fastened to the pocket;

Fig. 2 is a plan view of the invention, one of the arms of the rule omitted for the sake of clearness;

Fig. 3 is a side elevation of a rule and my attachment fastened thereto;

Fig. 4 is an end elevation of the same;

Fig. 5 is a perspective of the invention; and

Fig. 6 is also a perspective of a slightly modified form.

Referring now to the drawings, and especially to Fig. 5, it will be seen that the invention comprises an attachment for a rule that is preferably struck from a small single blank of metal and is formed with what I term a main body portion 1, which portion may be marked with the graduations 2, and

is also provided with several holes 3 so that the same may be nailed to one arm of a rule 4.

At the lower end of body portion 1, the metal is slightly reduced as at 5, and then bent slightly upwardly and then downwardly to form the resilient retaining clip 6, the end of this clip also being slightly bent upwardly as at 7, so that the same will slide easily at first over the fold of a pocket.

Fig. 1 shows the rule 4, with the clip 6 over such a fold.

At the upper end of the body portion an arm 8 is provided that is bent downwardly as at 9 at an angle of 90 degrees for a slight distance and is designed to contact with a side face of the arm to which the body portion is nailed or screwed. This arm 8 is formed at exactly 90 degrees to the body portion 1, and by having the downwardly bent portion 9 extending about half the length of the body portion when the attachment is secured to the rule by placing the portion 9 against the side of the arm of the rule before nailing the same to the rule the attachment is bound to be rightly alined, that is the arm 8 will be exactly at right angles to the rule.

This arm 8 is also graduated in inches and parts thereof so that the rule may be used as a square whenever desired.

Referring to Figs. 1 to 5 inclusively, it will also be seen that by having this offset portion 9, the arm of the rule that is adjacent to the arm to which the body portion is attached rests on the upper surface of the arm 9, when the rule is in a folded position. This is also an advantage, as the arms of the rule may be opened or shut in the ordinary way without determining which arm should be opened or closed first.

In Fig. 6, is shown a modification of the attachment, the only difference in construction being that the arm 10 is not offset from the body portion 11 but simply extends at right angles to it. It is provided with the spring clip 12, and with the graduations 13, and the small holes 14 so that the same may be nailed or screwed to the rule. With this form, however, care has to be taken that the attachment is correctly alined when being fastened to the rule, as it has no offset guiding portion as mentioned in the preferred form.

Also the adjacent arm of the rule fits under the arm 11 so that the rule has to be opened

from the side rather than as the fancy desires.

From the foregoing it will be seen that the attachment is exceedingly simple, may 5 be easily stamped out in great quantities with but relatively little expense, and may be quickly secured to a rule so that the attachment may be sold separately or may be nailed to the rule before it is sold.

10 With the preferred form it is impossible to get the attachment on in any other than the correct position if the bent portion 9 is held tightly against the side face of the arm of the rule to which the body portion is 15 attached.

Also by providing the body portion with the integral spring clip the rule cannot slip out of the pocket of the carrier.

It is to be understood that the attachment 20 after once being placed on the rule is designed to remain there, and in no way is it designed to be removed unless the nails or screws are forced out, which should only be done in case the attachment is destroyed 25 and it is desired to replace it.

Having thus described the invention, what I claim as new and desire to secure by Letters Patent is:

1. An attachment for a rule comprising a 30 body portion, the lower end of said body portion being bent away from the rule and then toward the rule to form a spring retaining clip, an arm at the upper end of said body portion extending at right angles to the body portion, said arm being graduated.

2. An attachment to be permanently fastened to a rule, comprising a body portion, the lower end being bent to form a clip, an

arm formed at the upper end of the body portion extending against one of the longitudinal edges of the rule and then outwardly at right angles to the body portion. 40

3. In combination with a rule, an attachment fastened thereto, said attachment formed from a single blank of metal, the attachment comprising a body portion fastened parallel with the member of the rule to which it is attached, the lower end of the body portion being bent away from contact with the said member and then toward the 50 said member again to form a spring retaining clip, an arm formed at the upper end of the body portion and formed to contact with one of the longitudinal edges of the said rule member and then at right angles to the 55 rule member and body portion so as to permit the rule to be used as a square.

4. In combination with a rule, an attachment fastened thereto, said attachment formed from a single blank of metal, the attachment comprising a body portion fastened parallel with the member of the rule to which it is fastened, the lower end of the body portion being bent away from contact with the said member and then toward the 60 said member to form a spring retaining clip, an arm formed at the upper end of the body portion and formed to contact with one of the longitudinal edges of the said rule member and then at right angles to the rule 65 member and body portion so as to permit the rule to be used as a square, said body portion and said arm being graduated.

In testimony whereof I affix my signature.

GEORGE H. FAHRENBRUCH.
